UNITED STATES PATENT OFFICE

HERMAN B. LAYMON, OF SPENCER, INDIANA

METHOD OF MAKING BAGS

Application filed January 10, 1930. Serial No. 419,918.

This invention relates to bags for the display and sale of eatables, such as nut-meats and other small articles, and has especial reference to the method of making the bags, 5 the present application being a combination case to an article application filed by me of even date herewith.

Another object of the present invention is to provide a simple, novel and economical 10 method of making bags of the above character, which may be arranged in an attractive display, and which will keep their contents fresh for a relatively long period.

With the above and other objects in view, 15 the invention further includes the following novel features and details of construction, to be hereinafter more fully described, illustrated in the accompanying drawings and pointed out in the appended claim.

20 In the drawings:

Figure 1 is a plan view of a blank or sheet which forms the body of the bag.

Figure 2 is a similar view of the bottom closure strip.

25 Figure 3 is a plan view showing the bottom closure strip in position and the sheet partly folded.

Figure 4 is an edge view of Figure 3.

Figure 5 is a plan view showing the sheet 30 completely folded.

Figure 6 is a like view of the completed bag.

Figure 7 is an end view of the same.

Figure 8 is a sectional view on the line 35 8-8 of Figure 6.

Referring to the drawings in detail wherein like characters of reference denote corresponding parts, the reference character 10, indicates a blank or sheet of material used 40 to form the body of the bag. This sheet is of thin, tough, transparent material of a flexible character, so that it may be readily folded and may be made of cellophane or other pyroxyline material.

45 In the manufacture of the bag use is also

made of a strip 11 of relatively heavy stiff material, and this strip is preferably provided with an offset portion or extension 12 at one edge. The strip 11 is of a length equal to the width of the finished bag and is placed 50 upon the sheet 10 along one edge and centrally of the length of the sheet as shown in Figure 3 of the drawings. One side of the sheet 10 is then folded over upon the strip 11 as shown at 13 in Figures 3 and 4 and the 55 opposite side of the sheet is then folded inward upon the strip 11 with the edges of the sheet overlapped as indicated at 14 in Figure 5 of the drawings. The side edges 15 thus provided, are creased and staples 16 and 17 60 are passed through the body of the bag and through the strip 11 as shown in Figures 6 and 7 of the drawings. The strip 11 thus forms a closure for one end of the bag.

The overlapped edges 14 are then secured 65 together by a suitable adhesive as indicated at 18, so that a tubular body or bag is formed which is open at its upper end.

The bag is especially designed for the reception of nut-meats and like small articles 70 and by providing the offset portion 12 and securing the body of the bag thereto by means of the staple 16, the contents of the bag are prevented from falling downward sufficiently far to reach the upper edge of the strip 11, so that the lower end of the bag will not be unduly bulged or distorted. Display or advertising matter may be placed upon the strip and as the transparent material of which the bag body is formed will thus lie flat upon the 75 face of the strip, the said advertising or display matter will not be distorted, but will present an attractive appearance and may be plainly read.

The invention is susceptible of various 80 changes in its form, proportions and minor details of construction and the right is herein reserved to make such changes as properly fall within the scope of the appended claim. 85

Having described the invention what is claimed is:—

The herein described method of making display bags consisting of placing a strip of relatively stiff material upon a sheet of flexible transparent material, folding said sheet over the ends of the strip with the edges of the sheet overlapped, creasing the sheet to provide a flat tubular body, stitching the material of the body to the strip so that the latter will form an end closure, and gluing the overlapped edges of the sheet.

In testimony whereof I affix my signature.
HERMAN B. LAYMON.
